ANCHORAGE DEVICE

Filed Jan. 28, 1926

UNITED STATES PATENT OFFICE

RALPH S. PIERCE, OF HINSDALE, ILLINOIS

ANCHORAGE DEVICE

Application filed January 28, 1926. Serial No. 84,432.

My invention relates to anchorage devices, and in one of its aspects, to such devices which employ sleeves having tapering bores and which are receivable within openings 5 provided in a wall or other support and which are adapted to be expanded into holding engagement with the support by means of expanding screws or rods driven into the sleeves. In such devices, the smaller ends of 10 the bores are placed innermost within the openings that are formed in the walls or other supports that are to receive the anchoring devices. Workmen frequently insert the sleeves wrong end to. To guard against this 15 wrong use of the sleeves, I form them with portions at the smaller ends of the bores that are in line with the bores, these portions desirably completely closing the smaller ends of the bores. In the use of an anchoring 20 sleeve thus constructed, the end of the sleeve that is to be inserted first is readily discerned.

In accordance with another feature of my invention, the expanding rod, which is received in the sleeve to be substantially coaxial 25 therewith, has a lateral portion or portions which find passage through the sleeve into direct holding engagement with the support. The expanding rod is desirably in the form 30 of a screw whose threads penetrate the sleeve laterally and preferably at intervals into holding engagement with the support.

In accordance with another object of the invention, I employ an expanding rod and a securing member extending along the expanding rod said expanding rod having a thread of a diameter to enter the securing member laterally when the rod is driven, the angle defined between the thread and a planar portion that includes the portion of 35 the axis extending from such thread to the entering end of the rod being less than sixty-five degrees.

In accordance with another feature of my invention, I employ an expanding rod within 45 and substantially coaxial with the sleeve and expanding said sleeve into engagement with the support and formed with intertwined threads of gentle slope. This structure enables the rod, thus threaded, to be driven as a nail and to be turned somewhat as a screw as

a result of the hammer blows thereon so that as it is forced into place, channel ways are formed which receive the threads and guard the rod from withdrawal.

I will explain my invention more fully by reference to the accompanying drawings in which Fig. 1 is a side elevation of the preferred form of expanding rod; Fig. 2 is a view in elevation of the complete anchorage device with the wall carrying it shown in section and an object supported by the expanding rod also shown in section; Fig. 3 is a longitudinal sectional view of the preferred form of sleeve; Fig. 4 is a view similar to Fig. 2 before reception of the anchorage device; and Fig. 5 is a view similar to Fig. 2 with the expanding rod shown mainly in section and the expanded sleeve also shown in section.

The anchorage device includes an expanding rod 1 preferably formed with a head 2 which is desirably conical. The rod is formed with intertwined threads 3 which are desirably deep and slope with respect to the axis of the screw less than forty-five degrees, the threaded portion of the rod from crown to crown of the screw thread being desirably of the same diameter as the unthreaded object holding portion of the rod which is adjacent the head. The sleeve or securing member 4 may be formed of cast metal such as iron or of ductile metal such as lead. The sleeve is desirably threaded throughout the length of its bore similarly to the threading of the expanding rod so as readily to take the threads of the rod, such threading of the sleeve being especially desirable if the sleeve is made of cast iron. The bore of the sleeve desirably tapers whereas the expanding rod does not taper, where it is surrounded by the sleeve, except at the inner end of the rod which has a formation 5 in the nature of a point. That is, the entering end of the rod is unthreaded and tapers to a point.

In the use of the anchorage device, the sleeve is first inserted, with the smaller end of the sleeve bore innermost, within the cylindrical opening 6 which is formed in the wall 7 or other support, this opening being of a size to snugly receive the sleeve. The

rod is next inserted into the sleeve, point first. It may be hammered into place, the rod turning as its screw thread follows or partially follows the threading of the sleeve. The threaded portion of the expanding rod is larger than the bore of the sleeve, the variation in size of the rod and sleeve increasing toward the inner end of the sleeve due to the tapering of the bore of the sleeve. The sleeve is consequently expanded, the expansion gradually increasing from the outer end of the sleeve to its inner end. The sleeve is sufficiently thin and the threading of the expanding rod is sufficiently deep so that the crowns of the threads of the rod will penetrate the sleeve and have direct engagement with the support. The interaction of the sleeve and the expanding rod is such that the threading of the rod will not continuously penetrate the sleeve but only at intervals, such as indicated at 8. The unthreaded portion of the expanding rod supports any suitable object 9 through which the rod is passed.

As viewed in elevation, Fig. 1, it will be observed that the angle defined between each thread and a planar portion that includes the portion of the axis extending from such thread to the entering end of the rod is less than sixty-five degrees. By thus sloping the threads, a lateral wedging action is caused upon the surrounding sleeve having a force greater than the force exerted on the sleeve axially of the nail whereby the sleeve is prevented from travelling inwardly with the nail but is held stationary with respect to the wall and with no material tendency to become bunched or buckled anywhere throughout its length. This characteristic enables the employment of a very thin surrounding sleeve which, if desired, may be readily penetrated by the crowns of the threads.

In order that the workmen may be guided in the use of anchoring sleeves that are circumferentially continuous throughout their length and have tapering bores, whether of the construction shown or of other construction, I provide the sleeve at the end thereof where the bore is smallest with a portion 10 which extends into line with the bore. In the preferred embodiment of the invention, the portion 10 is an integral part of the sleeve and is imperforate so as to close the sleeve at the end thereof where the bore is smallest. The point 5 of the expanding rod will find its way through the portion 10 of the sleeve and will inwardly extend the sleeve into gripping engagement with the wall portion at the bottom of the opening 6. The tapering end of the rod 1 is of greater width, at some portion thereof, preferably the upper or base portion of the tapered end than the narrower portions of the bore of the sleeve 4, whereby the sleeve is expanded into engagement with the surrounding wall of the hole in the support 7 to prevent this

sleeve from being crowded ahead as the rod is being driven, a result which I believe to be novel in the type of device illustrated. The tapering end ploughs its way through the narrower portions of the sleeve while also expanding these portions. While the bore of the sleeve is wider, at other places, than the tapered end of the rod in the device as illustrated, I do not wish to be thus limited nor do I wish to be limited to the preferred sloping of the threads.

Having thus described my invention, I claim:

In an anchorage, the combination with a support formed with a receiving opening; of a sleeve within said opening; and an expanding rod within and substantially coaxial with the sleeve and expanding said sleeve into engagement with the support and formed with intertwined threads, portions of the crowns of said threads extending through the sleeve into engagement with the support.

In witness whereof, I hereunto subscribe my name.

RALPH S. PEIRCE.
